UNITED STATES PATENT OFFICE.

CORNELIUS GRAY, OF WALSALL, ENGLAND.

STAIR-CARPET FASTENER.

1,300,214.

Specification of Letters Patent.

Patented Apr. 8, 1919.

Application filed February 12, 1917. Serial No. 147,994.

To all whom it may concern:

Be it known that I, CORNELIUS GRAY, a subject of the King of Great Britain and Ireland, and residing at 12 Tasker street, 5 Walsall, in the county of Stafford, England, have invented an Improved and Useful Stair-Carpet Fastener, of which the following is a specification.

This invention relates to improvements in 10 fasteners for stair carpets and has for its object to provide an improved device of the slotted bar and turn-button form of such fastener.

According to this my invention the stair 15 carpet fastener comprises a rail or bar of any suitable section notched at one or both ends. Each notch is adapted to receive a support which prevents lateral movement of the notched end of the rail or rod when the 20 said pillar part is in place. Attached to the said support, so that it can be moved about its axis, is an arm adapted to engage a notched end of the rail or bar to prevent its movement axially of the said support. Provision 25 is made for preventing the movement of the arm axially of its support and also for securing the said support in place.

In the accompanying drawings, which 30 illustrate one form of this my invention, Figure 1 is a part front view of a stair carpet fastener made in accordance with this invention, and

Fig. 2 is a part plan thereof.

This embodiment of my invention is shown 35 as comprising three parts, a rail or bar *a* and two supports *b*, *b*. The rail or bar *a* is employed to hold the stair carpet at the foot of a stair-riser in place of the well known rod. The flat rail or bar *a*, when in 40 place is parallel to the face of the riser and is retained in position there by means of swinging arms *c*, *c*, each carried by a short pillar *d* which is furnished with a stud *e* constituting a journal upon which the arm *c* 45 turns. The head *g* of each stud *e* prevents the detachment of this arm *c* from its pillar *d*. For fixing the supports *b*, *b* in place, preferably on the riser as shown in Fig. 1, each pillar *d* is provided with a flange *h* 50 having holes through which screws may be driven into the said riser.

When the stair carpet is in place it is retained in position behind the rail or bar *a*,

prevented from releasing it by the arms *c*, *c*, which then occupy the positions shown on 55 the right hand side of Fig. 1, and in broken lines in Fig. 2. The carpet is thus not liable to be released by accident, since any jar which produces a slipping of an arm *c*, only causes that arm to be moved downward by 60 its weight toward the bottom of the rail *a* where the movement is arrested by the carpet which thereafter prevents any further downward movement.

To release the carpet each arm *c* must first 65 be raised against the resistance of both gravity and friction and turned beyond the vertical. Then the rail *a* can pass outward along the pillars *f*, while the arms *c*, *c* are retained in open position by gravity, ready 70 for the replacement of the rail.

Obviously this invention is not limited to the construction shown in the drawings. For example instead of a pair of supports 75 *b*, *b* a single support *b* might serve for securing one end of a bar such as *a* the other end of this bar being inserted under a suitable stop or staple before passing the notched end along the single pillar *d*.

The bar also may be of any desired section that has a notched end adapted to engage a suitable pillar, or a part of an arm, so that lateral movement of the said bar is prevented. Again, a pillar part may be furnished with other means than a flange for 85 fixing it in place and be otherwise shaped for attachment to the rotatable arm.

I claim:—

A stair carpet fastener comprising in combination a stair rod having a notch at each 90 extremity, said notch opening on the axis of said rod, a pillar adapted to engage each notch and prevent movement of the rod transversely thereof, a rotatable arm pivoted axially upon said pillar and adapted 95 to prevent movement of said rod axially along it, a base on and at right angles to the axis of the pillar and means for securing the base to the surface of a body and at right angles to the axis of the pillar, substantially 100 as described.

CORNELIUS GRAY.
